UNITED STATES PATENT OFFICE

THEODORE JOHNSON, OF ERIE, PENNSYLVANIA, ASSIGNOR TO JOHNSON METAL PRODUCTS CO., OF ERIE, PENNSYLVANIA

CASEMENT WINDOW

Original application filed February 11, 1928, Serial No. 253,744. Divided and this application filed July 28, 1928, Serial No. 296,014. Renewed September 1, 1931.

This invention relates to casement windows of that type wherein the window sashes swing outwardly, and it is an object of the invention to provide a structure embodying 5 a locking means permitting a screen to be disposed over the inner face of the frame and in close contact therewith in a manner whereby said screen offers no hindrance or obstruction to the desired adjustments of the window 10 sashes.

It is also an object of the invention to provide a structure of this kind comprising a plurality of window sashes coacting with a single frame together with means associated 15 with said window sashes for locking all of the sashes in closed position or selectively locking a single window sash independently of the remainder.

An additional object of the invention is to 20 provide a casement window with a locking mechanism for the window sash or sashes including an operating member which is at all times carried by a stationary part of the casement frame.

25 The invention consists in the details of construction and in the combination and arrangement of the several parts of my improved casement window whereby certain important advantages are attained and the 30 device rendered simpler, less expensive and otherwise more convenient and advantageous for use, as will be hereinafter more fully set forth.

The novel features of my invention will 35 hereinafter be definitely claimed.

In order that my invention may be the better understood, I will now proceed to describe the same with reference to the accompanying drawings, wherein:—

40 Figure 1 is a view in inside elevation of a casement window structure constructed in accordance with an embodiment of my invention;

Figure 2 is an enlarged sectional view taken 45 substantially on the line 2—2 of Figure 1;

Figure 3 is a fragmentary sectional view on substantially the same line as Figure 2 but showing certain of the parts in different positions;

50 Figure 4 is a view in side elevation of the

head comprised in the operating means for the locking disc;

Figure 5 is a view partly in section and partly in elevation, the line of section being taken substantially on the line 5—5 of Figure 2;

Figure 6 is a detailed sectional view taken substantially on the line 6—6 of Figure 5;

Figure 7 is a view somewhat similar to Figure 6 but showing the locking disc in a 60 second position;

Figure 8 is a view in front elevation of the locking disc unapplied.

As disclosed in the accompanying drawings, F denotes a casement frame of requisite 65 dimensions and design and which has hinged-ly connected with its jambs or side members the outwardly swinging windows W which, when fully closed, have close engagement with a central vertical post P interposed be- 70 tween the top and bottom members 1 of the frame, said post being preferably positioned at the center of the frame.

The post P, as herein disclosed, comprises a substantially T-member or iron with 75 the web flange 2 outwardly disposed and having its outer longitudinal or vertical margin defined by a laterally directed flange 3 herein disclosed as perpendicular with respect to the web flange 2. The outer or free 80 vertical stiles 4 of the windows W are of a stepped character providing the contact portions a and b having direct engagement respectively with the marginal portion of the head 5 of the post P and with the flange 3. 85 The portion of each of the stiles 4 having contact with the head 5 has the usual bevel 6 thereby providing an internal shoulder with which a suitable locking element is adapted to engage for maintaining a window 90 W in fully closed position. The bevel performs its usual function in deflecting any leakage of air through the outer joint between the sash and casing away from the inner joint between the baffle and the casing. 95

At a desired point intermediate its ends and preferably at substantially the center of the post P is mounted for rotation a head 7, said head having at the axial center of its inner end a shank 8 directed through a 100

suitably positioned opening 9 in the head 5 of the post P and to the inner or inserted end portion of this shank is suitably affixed a locking disc 10. This disc 10 is formed on a desired radius of a circular design in excess of a semi-circle and wherein a portion or side of the disc is substantially straight.

The web flange 2 is provided therethrough 10 with an opening 11 through which a peripheral portion of the disc 10 is adapted to project and when the disc 10 is turned or adjusted to have its major diameter substantially horizontally disposed, said disc will 15 have contact with the internal shoulders 6 to effectively lock both of the windows W when in fully closed position.

By turning the disc 10 to bring the substantially straight portion thereof to the 20 right the left window W will be locked in fully closed position independently of the right window and under which conditions said right window may be adjusted as desired into open position. By bringing the 25 substantially straight portion of the disc 10 to the left the right window will be locked in fully closed position and the left window be released for desired opening movement.

Disposed over the inner face of the frame 30 F and in close contact therewith is a screen S, the lower member of which resting upon a fixed clip C carried by the lower member of the frame while the upper portion of the applied screen is engaged by the clips C' 35 pivotally connected for swinging movement, as at c, with the upper member of the frame. By turning these clips C' upwardly out of the way a screen may be readily applied or removed and when the clips C' are swung 40 downwardly to engage over the upper portion of the applied screen said screen in connection with the lower clip C is effectively maintained in desired position.

The central portion of the cloth 12 of the 45 screen is provided with a relatively small opening 14, the portion of the cloth 12 defining said opening 14 being reinforced by a suitable binding 15.

This opening 14 is of a size to readily engage over the applied head 7 so that the central portion of the screen will have close contact with the inner face of the post P, or more particularly the head 5.

The outer portion of the head 7 has pivotally connected therewith, as at 16, an elongated arcuate handle 17 which provides convenient means for effecting the desired rotation of the head 7 and the associated disc 10 for locking or releasing the windows W as desired. In this operation the handle 17 may be readily swung into a lateral position to assure an effective leverage action but when it is desired either to apply or remove the screen S, this handle may be swung into 60 an intermediate position or in a position con-

stituting substantially a continuity of the outer end of the head 7. This adjustment of the handle 17 together with the radius of its curvature will permit the screen S to be readily swung upon its lower edge as a fulcrum resting on the clip C to either apply or remove the screen.

Each of the windows W has associated therewith a locking bar 18 for moving said window into open or closed position as desired, said locking bar being disposed through and coacting with a clip C. The particular type of locking bar and associated mechanism is described and claimed in an application executed on even date herewith and, therefore, it is not believed that a more complete explanation and illustration is necessary in connection with the present disclosure.

This application is a division of my application Serial No. 253,744 filed February 11, 1928.

From the foregoing description it is thought to be obvious that a casement window constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A latching means adapted for use with a frame and swinging members comprising an approximately semi-circular disc rotatably supported by the frame between the swinging members, said disc having one side portion substantially straight, said disc when in one position engaging the swinging members when closed to hold the same in said closed position, said disc when in a second position holding one of the members closed and permitting the other to be opened and when in a third position holding the last named member closed and permitting the first named member to swing open.

2. A latching means adapted for use with a frame and swinging members comprising an approximately semi-circular disc rotatably supported by the frame between the swinging members, said disc having one side portion substantially straight, said disc when in one position engaging the swinging members when closed to hold the same in said closed position, said disc when in a second position holding one of the members closed and permitting the other to be opened and when in a third position holding the last named member closed and permitting the

first named member to swing open, said disc being of a circular design in excess of a semi-circle.

3. A latching means adapted for use with
5 a support having a central post, swinging members at opposite sides of the post and movable with respect thereto comprising a disc adapted to be rotatably supported by the post, said disc having one side portion arcu-
10 ate and its opposite side portion substantially straight, the major diameter of the disc being of a length when the disc is in applied position to engage both of the members when fully closed, said disc when its substantially
15 straight portion is positioned adjacent to one member has holding engagement with the shoulder of the second member with the first member free for swinging movement.

In testimony whereof I hereunto affix my
20 signature.

THEODORE JOHNSON.
